UNITED STATES PATENT OFFICE.

DAVID ALEXANDER, OF HOMINY, OKLAHOMA.

ENVELOP.

1,100,703.

Specification of Letters Patent. Patented June 23, 1914.

Application filed December 29, 1910. Serial No. 599,828.

To all whom it may concern:

Be it known that I, DAVID ALEXANDER, a citizen of the United States, residing at Hominy, in the county of Osage, State of Oklahoma, have invented certain new and useful Improvements in Envelops; and I do hereby declare the following to be a full, clear, and exact description of the invention, such as will enable others skilled in the art 10 to which it appertains to make and use the same.

This invention relates to envelops of the class constructed to prevent surreptitious access or to envelops so constructed that any 15 attempt to open the same by unauthorized persons will be disclosed, and has for its object to improve the construction and increase the efficiency and utility of devices of this character.

With this and other objects in view, the invention consists in certain novel features of construction as hereafter shown and described, and then specifically pointed out in the claim, and in the drawings illustrative 20 of the preferred embodiment of the invention, Figure 1 is a view of the envelop in closed position. Fig. 2 is a section enlarged on the line 2—2 of Fig. 1. Fig. 3 is a perspective view of the locking member detached. Fig. 4 is a perspective view of the receiving member detached.

The improved device may be applied to envelops of various forms, but for the purpose of illustration, is shown applied to a 35 conventional envelop in which—

10 represents the body portion and 11 the closure or sealing flap. The closure flap is provided with the usual adhesive material indicated at 12, whereby the envelop may 40 be "sealed" in the usual manner. Attached to the "point" of the closure flap 11 is a locking bar 13 of suitable metal and fastened by lateral "points" or spurs 14 to the flap 11, with its free end extending beyond 45 the point of the flap and provided with a return bend 15 at its terminal.

Secured within the body of the envelop adjacent to the terminal of the flap 11 is a receptacle 16, preferably in flat box-like 50 form and with a relatively narrow slit 17 in one end to receive the portion 15 of the

member 13. Secured within the receptacle 16 is a transverse bar 18 beneath which the point of the member 15 engages when the member 13 is forced into the receptacle as 55 illustrated in Fig. 2. It will be obvious that when the member 13 with its return bend or barb-like terminal 15 is inserted into the casing 16 and the point of the member 15 expands beneath the cross bar 18, it will be 60 impossible to withdraw the member 13 without destroying some portion of the device, and thus revealing the fact that the envelop has been tampered with.

With an envelop thus constructed it will 65 be obvious that after the contents have been deposited therein and the adhesive edges of the flap 11 moistened, the envelop may be securely "sealed" and locked by inserting the barbed end 15 of the member 13 into the 70 slit 17 of the member 16 and forcing the same downwardly until the barbed end engages beneath the bar 18, and pressure applied to the adhesive edges of the flap, and it will be impossible to open the envelop 75 without detection, as will be obvious.

The improved device is simple in construction, can be inexpensively manufactured and applied to envelops of various sizes and forms and to envelops constructed 80 from various materials, and it is not desired therefore to limit the improved device to any particular size or form or to envelops employed for any particular purpose. The member 16 will be arranged within the envelop and a cleft formed through the body portion 10 opposite the opening 17 to admit the barbed terminal of the member 15 of the member 13. The member 13 and its barb 15 may be of any suitable metal, but preferably 90 of brass or other non-corrosive metal.

What is claimed, is:—

The combination with an envelop provided with a sealing flap, of a metallic locking bar fastened to the outside of the flap, 95 one end portion of the bar projecting beyond the flap and terminating in an upwardly bent hook portion, a box-like member secured inside the envelop at a point adjacent the terminal of the flap when the latter is closed, said box-like member having a slot in the end thereof adjacent to the en-

velop flap, said slot being designed to receive the adjacent portion of the locking bar, and an inclined cross bar extending transversely within the box-like member and 5 adapted to receive the hook of the locking bar and adapted to act as a keeper for the latter.

In testimony whereof, I affix my signature, in presence of two witnesses.

DAVID ALEXANDER.
